UNITED STATES PATENT OFFICE.

ANTHONY H. VAN ZEE, OF ORANGE CITY, IOWA.

GENERATION AND IGNITION CONTROL DEVICE.

Application filed February 7, 1927. Serial No. 166,582.

My invention relates to a self-lighting lamp or the like, and it is my object to provide automatic mechanism for lighting a lamp of the gasoline type at a predetermined time.

More specifically, it is my purpose to provide mechanism for, first heating the generating coil of a gasoline mantle lamp or the like, and then, after a sufficient period of time has elapsed to heat the coil to generation point, to automatically open the feed valve of the lamp.

A further object of the invention is the providing of a simple timing and operating mechanism for accomplishing the two steps of heating the generating coil and then, after a predetermined time, opening the feed valve of the lamp, said operating mechanism being initially set in action at a predetermined time by the timing mechanism and thence serving in itself to time the succeeding operations.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is an assembly view of the lamp operatively connected with the lighting mechanism, the operating mechanism being set for operation.

Fig. 2 is a detail sectional view taken on the line 2—2 of Fig. 1.

Fig. 3 is a detail sectional view taken on the line 3—3 of Fig. 1.

Fig. 4 is a detail sectional view through the ignition device.

The use of automatic lighting mechanism for chicken houses and the like has become very widespread; automatic clock controlled electric lighting mechanism has proven successful. However, a great many farms are not equipped with electric power and if artificial lighting is to be used, it must be by gasoline or acetylene or the like.

The purpose of the present invention is to provide an automatic time controlled mechanism where generation and ignition are both necessary.

I have used the reference character 10 to indicate generally a support for the lamp and the other mechanism. An ordinary type of gasoline mantle lamp is illustrated, in-

cluding the gasoline tank 11, feed valve 12, generating coil 13, mantle 14 and chimney 15. Secured to the mantle post 16 is a bracket 17 which supports a cup 18 containing refractory material 19 such as asbestos or mineral fiber. The cup just described forms part of my invention and is provided for the purpose of heating the coil 13.

Alcohol is placed in the cup and is absorbed by the refractory material. This is done at the time the mechanism is set in the evening for operation upon the ensuing morning. In order to ignite the alcohol at the proper time, I provide a spark gap formed between the edge of the cup 18 and an electrode 20 supported upon a block of insulating material 21 which in turn is secured to the end of the bracket 17. The secondary circuit of an induction coil 22 includes the wire 23 connected to the electrode 20, the wire 24, which is grounded to the lamp supporting structure 10, and the cup 18, which also is grounded to the mantle structure 10, through the lamp.

The primary of the induction coil 22 includes a wire 25, a source of current not shown, a wire 26, a brush 27, a commutator disc 28, which is grounded to the base 10 through a shaft 29 to which it is secured, and the clockwork frame 30 in which the shaft 29 is journalled, and the wire 24. The commutator disc 28 is rotated by a spring motor 31 connected to the shaft 29 by a train of gears 32, 33, 34 and 35. The rotation of the commutator is controlled by a brake shoe 36 acting against a brake wheel 37 connected to the train of gears just described by the secondary train of gears 38, 39, 40, 41 and 42. The commutator 28 may thus be set in the proper position by manually actuating the brake shoe 36 through the medium of the lever 43 secured to the shaft 44 which carries the brake shoe 36. A spring 45 tends to normally maintain the brake shoe in engagement with the brake wheel 37. In thus setting the commutator, it is allowed to rotate to a position where the brush 27 rests in contact with the insulated sector 46.

It will now be seen that upon release of the brake by the proper timing mechanism, the commutator will rotate under the urge of the spring 31, causing the brush 27 to complete the primary circuit of the induction coil 22, producing a spark between the electrode 20 and the cup 18. The brush 27 is

of spring material, placed under sufficient tension so that when the commutator has rotated less than one revolution, the brush will slip through a slot 47 and thus break 5 the circuit while allowing the remainder of the actuating mechanism to continue in operation.

In order to release the brake 36 at the proper time interval, I provide an ordinary 10 clock mechanism, indicated generally at 48 and including a lever 49 actuated in the direction of the arrow 50 at a predetermined time interval. The mechanism for timing and actuating the lever 49 may be of the type 15 ordinarily employed to actuate the alarm of an alarm clock, and includes the shaft 51^a, which is so connected with a spring lever 75 as to allow said lever to move suddenly in a direction longitudinal of the shaft 51^a at a 20 certain predetermined time, determined by the setting of the shaft. The lever 75 is the lever which in an ordinary alarm clock, releases the clapper of the bell by such movement longitudinal of the shaft 51^a.

25 In place of the usual bell clapper, I employ a disc 76, which is secured upon the shaft 77 carrying the lever 49 and which is provided with a finger 78, normally engaged by the laterally turned end 75^a of the lever 75. The end 75^a of the lever 75 is provided with a bevelled cam face 75^b and when the shaft 77 is rotated in a direction opposite to that of the arrow 50 to reset the brake mechanism with the brake engaged, the finger 78 will engage this inclined face 75^b and move the spring lever 75 laterally to allow the finger to clear the end of the member 75^a, whereupon the spring lever 75 will return to the position shown in Fig. 5 engaging the 35 finger 78 and locking the lever in the position shown in Fig. 1. When the lever 75 moves laterally at the time set, the end 75^a of the lever will release the finger and allow the lever 49 to move in the direction indicated by the arrow 50. The setting of the 40 shaft 57^a is indicated by the dial 52. One end of the lever 49 is connected by a link 53 to the lever 43 and as the lever 49 rotates, it will swing the brake shoe 36 away from 45 contact with the brake wheel 37.

50 The mechanism for opening the valve 12 is timed by the rotation of the shaft 29, which, due to the gear train acting in the usual manner as a governing mechanism, will rotate at a predetermined rate of speed. A drum 53 is rotatably secured upon the shaft 29 and may be locked thereon by means of a slide pin 54 extending through the drum and into an opening in the disc 28. The 55 pin 54 is normally extended into the opening in the disc but may be withdrawn to change the setting of the drum 53 relative to the disc in order to adjust the timing mechanism which will now be described.

55 A cord or cable or the like 55 is secured to

and wound about the drum 53 and thence extended through a guide 56 to the latch 57 of the valve operating lever 58. The lever 58 is secured to the valve 12 and is urged downwardly by a spring 59. The latch 57 is 60 pivoted at 60 to the lever 58 and is urged by a spring 61 into engagement with a keeper 62 secured to the clockwork cover 63. The rotation of the disc 28 is in the direction of the arrow 64. It will now be seen that, upon release of the brake shoe 36, the disc 28 and drum 53 will commence rotating, an igniting spark occurring during the first revolution and the cord 55, being then wound upon the drum 53 until the slack portion of the cord has been drawn tight whence the latch 57 will be released and the lever 58 allowed to spring downwardly, to open the forward valve 12. The alcohol in the cup 18 has, during this interval, produced a flame to heat the coil 13 and when the valve is opened and a spray of vapor is delivered to the mantles 14, the same flame will serve to light the mantle.

Simultaneously with the opening of the 90 valve 12, the brake mechanism will be again applied to stop the rotation of the actuating mechanism. This is accomplished by means of a cable 66 secured to the end of the lever 58 extending through a guide 67 and thence 95 secured to the lever 49. Sufficient slack is left in the cable 66 so that the lever 49 will not be acted upon until the lever 58 has reached the lower limit of its movement. It will be seen to be necessary to stop the actuating mechanism in order that the pressure 100 upon the cable 55 may not be increased to a point where there is a likelihood of injuring the latch 57. In order to reset the mechanism, it is necessary to reset the brush 27 and the disc 38 in their proper positions as shown in Fig. 1 and thence to unwind the 105 cable 55 and return the latch 57 to its engagement with the keeper 62.

110 Some changes may be made in the construction and arrangement of the parts of my invention without departing from the real spirit and purpose of my invention, and it is my intention to cover by my claims, any modified forms of structure or use of 115 mechanical equivalents, which may be reasonably included within their scope.

I claim as my invention:

1. In an automatic generation and lighting device, a generation coil and a burner, a 120 cup beneath said coil, an induction coil, an ignition device having a spark gap adjacent said cup and included in the secondary circuit of the induction coil, actuating mechanism including a commutator adapted to 125 make and break the primary circuit of said induction coil, braking means active upon said actuating mechanism, time controlled means for releasing said braking means, and a feed valve, opened by said actuating mech- 130

anism a predetermined period after said actuating mechanism has been set in motion by release of the braking means.

2. In an automatic generation and lighting device, a generation coil and a burner, a cup beneath said coil, an induction coil, an ignition device having a spark gap adjacent said cup and included in the secondary circuit of the induction coil, actuating mechanism including a commutator adapted to make and break the primary circuit of said induction coil, braking means active upon said actuating mechanism, time controlled means for releasing said braking means, a feed valve, opened by said actuating mechanism a predetermined period after said actuating mechanism has been set in motion by release of the braking means, and means for re-engaging the braking means directly after the feed valve has been opened.
3. In an automatic generation and lighting device, a generation coil, a burner, and a feed valve, a spring-urged lever operatively connected with the valve, a latch to maintain the lever in inoperative position, actuating mechanism adapted to be set in motion at a predetermined time interval, an element connecting the actuating mechanism with the latch in such manner as to transmit movement to release the latch after a predetermined amount of movement of the actuating mechanism, and an ignition device operated by said actuating mechanism near the beginning of its movement.
- 35 4. In an automatic generation and lighting device, a generation coil, a burner, and a feed valve, a spring-urged lever operatively con-

nected with the valve, a latch to maintain the lever in inoperative position, actuating mechanism adapted to be set in motion at a predetermined time interval, an element connecting the actuating mechanism with the latch in such manner as to transmit movement to release the latch after a predetermined amount of movement of the actuating mechanism.

5. In an automatic generation and lighting device, a generation coil and burner, a cup for heating the coil, an ignition device having a spark gap adjacent said cup, and time-controlled mechanism for controlling the flow of current to said ignition device.

6. In an automatic generation and lighting device, a generation coil and burner, a cup for heating the coil, an ignition device having a spark gap adjacent said cup, a time-controlled commutator comprising a rotating disc having a slot and an insulated portion, and a brush coacting with said commutator, adapted to slip through said slot after a revolution of the commutator, and an electric circuit including said commutator, said brush, and the ignition device.

7. In a generation device, a generating coil, a cup for heating said coil, an ignition device including an electrode spaced from the edge of the cup and insulated therefrom, and time-controlled mechanism having a member forming part of an electric circuit including the cup and the electrode.

Signed this 31st day of January, 1927, in the county of Woodbury and State of Iowa.
